ROTATABLE DISPLAY RACK

Edward B. Saltz, Milwaukee, Wis.

Application October 24, 1958, Serial No. 53,124

Term of patent 14 years

(Cl. D80—9)

Fig.1

Fig.2.

Fig.3.

Fig.4.

Fig.5.

Fig. 1 is a side elevational view of a rotatable display rack, showing my new design;

Fig. 2 is an enlarged top plan view of one of the shelf members;

Fig. 3 is a side elevational view of the shelf member shown in Fig. 2, all sides being the same in appearance as indicated in Fig. 2;

Fig. 4 is a transverse sectional view taken along line IV—IV of Fig. 1; and

Fig. 5 is a transverse sectional view taken along line V—V of Fig. 1.

I claim:

The ornamental design for a rotatable display rack, substantially as shown and described.
